UNITED STATES PATENT OFFICE.

CHARLES SHOETTLE, OF CHICAGO, ILLINOIS.

STUMP-PULLER OR LIFTING-MACHINE.

SPECIFICATION forming part of Letters Patent No. 726,581, dated April 28, 1903.

Application filed April 30, 1902. Serial No. 105,415. (No model.)

To all whom it may concern:

Be it known that I, CHARLES SHOETTLE, a citizen of the United States, and a resident of Chicago, Illinois, have invented certain new and useful Improvements in Stump-Pullers or Lifting-Machines, of which the following is a specification, reference being had to the accompanying drawings, forming a part thereof.

The purpose of this invention is to provide an improved mechanism for such purposes in the nature of lifting as require extreme power for comparatively short movement, and in detail it is specifically adapted for stump-pulling.

It consists in the means shown and set out in the claims, by which a threaded lifting-rod is operated upon by two lifters alternately, each lifting against a nut on the rod, each nut being rotated while the lifting is being performed against the other nut to give it a new position for the next lifting action against it.

It consists, further, in the features of construction of the lifting means and means for driving the same and for connecting the lifting movements with the nut-operating movements and for adapting the entire lifting mechanism to the exigencies of stump-pulling, as particularly set out in the claims.

In the drawings, Figure 1 is a side elevation of my machine; Fig. 2, an end or edge elevation of the same. Fig. 3 is a detail section at the line 3-3 on Fig. 4. Fig. 4 is a top plan omitting the supporting-trucks, the leg-timbers being broken away at one end. Fig. 5 is a detail section at the line 5-5 on Fig. 4. Fig. 6 is a detail side elevation of a gearing-bracket and a gearing-train thereon for operating the lifting-screw. Fig. 7 is a detail plan of one of the gears of the screw-operating train.

In the drawings, 11 are the end supports of a frame, which comprises a top sill 2 and side trusses 3 3 for supporting the stump-pulling mechanism. This mechanism comprises a threaded lifting-rod 4, on which are two nuts 5 5^a, which operate as stops for two lifters 6 and 7. These lifters are levers, one of which, the lever 6, is fulcrumed at 8 on the sill 2, while the other is fulcrumed at 9 on the lower end of the suspending-links 10, but connected by links 11 with the lever 6. The lever 6 extends from its fulcrum 8 in the op-

posite direction from the connection with the links 11 to a point where it is operated upon by the power mechanism, and between its fulcrum and the point of application of the power—that is, on the opposite of the fulcrum from the connection of the links 11—it has pivoted to it between its side bars a collar 12, which is loose on the rod 4 below the upper nut 5, (but not immediately in contact with it, as hereinafter explained.) To the lever 7, between its fulcrum and its connection to the link 11, there is similarly pivoted between its side bars a collar 13, below but not immediately in contact with the lower nut 5. It will be seen that this arrangement of levers is such that when the lever 6 is lifted at the point of application of the power the collar 12 is lifted with it, and the collar 13, and thereby the lever 7, is lowered, and that when said lever 6 is depressed at the point of application of the power reverse movement of the lever 7 occurs, so that said two levers considered at the point of pivotal connection thereto of the collars 12 and 13 alternately approach and recede from each other, each alternately rising and falling along the rod 4, their rising movements—which are their lifting movements—alternating with each other. For certain specific purposes hereinafter explained the collars 12 and 13 are separated from the nuts, which respectively afford stops, by means of which they lift the rod by other parts; but these other parts are all free to move on the rod, so that the lifting action is transmitted directly from the collars pivoted to the lifting-levers, respectively, to the nuts above them. Considering this action independently of all accompanying details and features it will be noticed that when one lever—as the lever 6, for example—is lifting against the upper nut 5 the lever 7 is withdrawing the collar 13 from the lower nut 5^a. If now means be provided for screwing the nut 5^a down on the rod, so as to follow the retreating lever 7, then when the movement is reversed and the lever 7 lifts the collar 13 it will lift against the nut 5^a at the lower position to which said nut has followed the descent of the lever, and the upper lever 6 will be descending and carrying down the collar 12, while the lower lever is lifting against the nut 5^a, and means being

provided for causing the nut 5 to be carried down on the rod to follow the descent of the lever 6 at the next change of direction of the movement the upper lever 6 will lift 5 against the nut 5 at a still lower position, and thus each alternation will give the lifters a lower hold on the rod, which will have been obtained by screwing down the nuts without performing such action of the nuts while 10 there is strain upon them; but, on the contrary, in the interval during which they are entirely free from the weight or strain of lifting. I provide means for rotating the nuts in the intervals of the lifting action against 15 them, respectively, by means of a gear-train connected with a train for applying the lifting power to the lever 6. This train mechanism will now be described.

The nuts 5 5^a are substantially interiorly 20 threaded gears, and they may be hereinafter referred to as the "gear-nuts." A gearing frame or hanger 14 has two bearings or sleeves 15 15, by which it is mounted on the rod 4, the upper collar 12 being lodged on the rod 25 between these bearings so as to operate in the lifting action underneath and upward against the upper of said bearings, and immediately above said upper bearing is the upper gear-nut 5, so that the lifting action of 30 the collar is transmitted through the bearing 15 directly to the gear-nut precisely as if the collar were lodged immediately under the nut. The lower gear-nut 5^a is located immediately below the lower bearing 15, and immediately below said gear-nut on the rod is 35 a spacing-sleeve 16, which is merely for the purpose of covering the distance from the lower collar 13 up to the gear-nut 5^a, by which it lifts the rod. In the above description 40 certain parts designed to accommodate the lateral swing and pull to which the rod 4 will be subjected in stump-pulling are not taken into consideration, but should be noticed. Thus the lower end of the upper bearing 15 is convex and seats in the collar 12, whose upper end is correspondingly concave, and below the end of the sleeve 16 and above the collar 13 there is a similarly-formed 45 rocker 18, which seats similarly in the upper 50 concave end of the collar. The interposition of the seats does not affect the action, except in so far as they prevent cramping of the parts or bending of the rod 4 by the side strain to which it may be subjected. On the 55 hanger 14 there is journaled a shaft 19, having on it at upper and lower ends twin gears 20 and 20^a, meshing, respectively, with the gear-nuts 5 and 5^a. These twin gears are 60 loose on the shaft 19, but have frictional driving connection with said shaft, the upper gear 20 being directly in contact with the lower side of a beveled pinion 21, and the lower gear 20^a being in contact with a washer or friction-plate 22 underneath it, the shaft 19 having on it a nut-head 23, by which it is 65 stopped on the upperside of the beveled pinion 21, and having at the lower end, which pro-

trudes below the washer or friction-plate 22, a spring 24, which is stopped by a nut 25 on the threaded end of the shaft, by which the tension of the spring may be adjusted to cause the pinion 21 at the top and the friction-plate 22 at the bottom to press more or less tightly and with greater or less friction upon the twin gears 20 and 20^a, respectively, 70 to cause them to drive the gear-nuts 5 and 5^a, respectively, when not resisted by greater frictional or more positive resistance. On the frame there is mounted a wheel 26, having a crank-shaft 27, and on the wrist 28 of said 75 crank-shaft there is pivoted a short link or pitman 29, which is pivotally connected to the lifting-lever 6 to operate it with vibratory motion necessary to produce the actions already described. This wheel may be rotated by any 80 means. I have shown a crank-handle by which it may be rotated by hand; but in practice power from any suitable motor may be applied to drive it at any desired speed. On the bracket or hanger 14 there is journaled a shaft 85 30, having a bevel-gear 31, meshing with the pinion 21. About the axis of the wheel 26 there is pivoted a gear-frame 32, in which is journaled a shaft 33, having a pinion 34, meshing with the gear 26, while on the other end 90 of the shaft there is a sprocket-wheel 35, from which a chain 36 extends around a second sprocket-wheel 37 on the opposite end of the shaft 30 from the pinion 31 and communicates power to said shaft, and pinion, and thereby to the remainder of the train or trains 95 on the bracket or hanger 14, for it will be noticed that there are virtually two trains branching from a single source, one comprising the gear 20 and gear-nut 5, the other gear 100 20^a and gear-nut 5^a, and these trains, which may represent any more extended train which may be found under some circumstances convenient to employ, may be hereinafter referred to as the "gear-nut trains." A link 105 38 connects the two gear-frames 14 and 32, so that the oscillation of the former, which may take place under the stress of the lifting in direction more or less oblique, will be communicated to the latter frame and prevent 110 the slackening or straining of the drive-chain 115 36, which transmits the power from one frame to the other.

Considering the mechanism thus far described, it should be noted that upon the rotation of the gear-wheel 26 by hand or power the lifting-levers will be vibrated in the manner already described, alternately approaching and receding from each other at the points at which the collars 12 and 13 are pivoted to 120 them, respectively, for the purpose of lifting against the nuts 5 5^a, respectively, and that during all such movement in both directions the gear-trains described tend to keep both the gear-nuts rotating; but it will be noticed 125 that the rotation of both the nuts is transmitted frictionally from their respective trains and that neither will rotate whenever 130 the resistance to such rotation is greater than

the driving friction. It will be evident, also, that whichever nut is taking the lifting pressure from the lifter will be exposed to a strain by friction greatly in excess of any normal driving friction which will be suitable merely to drive the nut when it is loose and free on the rod, and that therefore although both trains leading to both nuts are continuously under power, so far as the frictional connection may transmit it, only the one which is free from the lifting strain will be rotated. The rotation of the wheel 26 in either direction will give identically the same lifting movement to the lifters 6 and 7; but in one direction it will rotate the nuts so that they will travel down on the rod, while rotation in the other direction would cause them to travel up. The direction of rotation which will cause them to travel down on the rods is manifestly the direction in which the wheel should be rotated for lifting action. The rate at which the lifting-levers approach and recede from each other evidently is not uniform, being maximum when the crank-wrist 28 is horizontal or approximately at that position and minimum, reducing to zero, when the wrist is passing over or under the center of the shaft. The gear-train which rotates the nuts is calculated to give the latter traverse on the rod at a speed a little greater, to allow for slipping at the frictional connection, than the maximum speed of separation or approach of the lifters. This causes the nut which is not under lifting strain to follow the retreating lifter at a speed which will take up any slack or play which it may be necessary to provide in the construction or adjustment to allow for the stretch of the parts under the extreme weight or strain of the lifting, and yet to overtake the retreating lifter (or the spacing element between it and the nut) and press against it with some little friction which may become sufficient to arrest the rotation even before the weight shifts into the nut thus descending. This insures the nut being in contact with a lifter or with a spacing element between them when the weight is shifted by the crank-wrist passing the center, so that there is no jolt or sag in the action; but the pull is perfectly continuous, the strain being transmitted by the driving friction of the train to a sufficient extent to take up all slack and stretch before the weight is transmitted by the rotation of the crank. It will thus be seen that automatically without attention from the operator under continuous rotation of the wheel 26 or other continuous means of vibrating the lever 6 the lifting will be carried on first against one nut and then against the other in continuous alternation without cessation of the lifting and without at any time lifting by the rotation of the nut or otherwise imposing upon the thread the strain of lifting while the nut is being rotated, but, on the contrary, always rotating the nut while it is free, except as under the driving friction it may be forced

into close contact with the part which is next to lift against it and with only so much pressure on its thread as is measured by the same driving friction.

For the purpose of lowering a weight or stump after it has been lifted or pulled without employing special mechanism or disconnecting the lifting or nut-operating mechanism above described it will be seen upon inspection that it will be necessary to provide some means to prevent the gear-nuts from rotating, merely by reason of the fact that they are not carrying the weight, because when the train is reversed, as will be necessary to run the nuts up on the rod instead of down, so as to permit the rod to be lowered instead of raised, the nuts having a greater speed than the lifters, as already explained, and running away from the lifters instead of toward them by reason of their reversed movement when they have once started away will be free entirely from the restraint of the load and will continue to run away until they have run out of mesh with their driving-gears, or at least one of them which first makes this start will thus run out of mesh, while the other carrying the load will continue to carry it, notwithstanding the lever which first carries the load may reverse its movement, because the nut against which the other lever should in turn operate to take the load will have escaped out of reach of it. If, however, means is provided independently of the friction which the load puts upon the gear-nuts to prevent their rotation except sufficiently to let them back on the rod at each change of movement of the lifting-levers as far and as far only as the movement of the lever next to follow will lower the rod the reversion of the direction of the train necessary to run the nuts up instead of down will be all that will be necessary to let the load down instead of lift it, the weight being carried first upon one nut and then upon the other and the nut which is not carrying the load being run up on the rod in the interval. For this purpose I provide a trip-lever 40, pivoted on the gear-bracket 14, midway between the gears 20 20^a, said lever oscillating radially with respect to the gears and sufficiently tight on its pivot to retain either position within its range of oscillation to which it may be moved, a tension-spring 41, coiled on the pivot-screw 42, serving for the purpose of thus checking it against accidental displacement. From the proximate faces of the two gears 20 20^a the teeth 43 43 project in such position that their path of rotation causes them to encounter the finger or terminal 44 on the lever 40 at the end which stands nearest the axis, said terminal finger and said tooth being beveled, so that by the encounter of their beveled faces the lever is forced outward at that end and inward at the other end, and at the outward position to which it is thus moved said finger is in position to be encountered by a stop-tooth 45, which projects from the face of the gear

and which is without the beveled edge which would enable it to pass the terminal, so that on the contrary, it collides against it and is locked to it, stopping the gear. I provide these trip and stop teeth in the gears at such intervals as will permit the gear to make so much of a rotation without being stopped as will give the gear-nut a travel on the rod equal to the movement of the lifter in each oscillation. The result of this construction is that when the train is reversed either lifter on which the weight may be resting being moved downward in its oscillation will let down the weight, the initial movement in that direction being accompanied by the release of the opposite gear-nut, and so by its rotation in direction to cause it to travel away from the lifter under it will continue until the rotation and consequent travel of the nut are stopped by the means described, and the lifter having overtaken it and pressing against it takes the weight and releases the other nut, which by the same action has been set free from the trip device, so that it can rotate as soon as it is relieved of the load, and it in turn runs away from its lifter to the limit of the rotation which is permitted by the trip device and is stopped by the said device and held until the lifter over-takes it and brings the weight of the load against it, and thus reverses the action. The load is thus lowered step by step, first by one lifter and then by the other, by the continuous action of the main train and the intermittent and alternate action of the branch trains to the gear-nuts.

In operating the mechanism described the train should be reversed for the purpose of lowering at the point at which the load shifts from one lifter to the other, or rather just after the load has shifted, and the nut which has been taking the weight is relieved by the shift. In order to throw the train which drives the gear-nuts out of connection with the lifting-train at any point, so that the power may be stopped and started again and allowed to run so as to bring the crank-wrist around to the proper point for taking up the action on the train with the reverse movement, as described, I provide a clutch device for connecting the sprocket-wheel 35 with the shaft 33 and a shifting-lever 49 for throwing this clutch into and out of engagement.

I have shown the mechanism above described on a suitable frame adapted to operate as a stump-puller and for that purpose to be transported from spot to spot, and for convenience in serving this purpose it is provided with a pair of wheels on each of the lower sills 50 50 on the end frames 11. The wheels 51 51 are mounted upon the cranked ends 52 52 of a lever-frame, which is conveniently made of iron bar, folded as shown in the drawings, with its neck 53 adapted to be lodged across the sill 50 and retained by suitable box 54. With this construction the

wheels may be swung to either end or toward either end of the sill, and the frame being provided with means for locking it down in position at which the wheels protrude below the sill the end to which the wheels are thus thrown will ride on the wheels, while the other end may drag. I provide the hooks 55 55 for securing the frame in position described, which being released will permit the wheels to rest upon the ground securely, taking the weight off the wheels.

I claim—

1. A stump-puller, or lifting-machine, comprising a threaded lifting-rod, two oscillating lifters and means for moving them up and down along the rod, nuts on the rod above the lifters respectively, affording stops by which the lifters may lift the rod in their respective upward movements, the upward movements of the two lifters alternating with each other, and means for rotating the nuts during the downward movements of the lifters with which they respectively coöperate to cause them to follow such downward movements.

2. A stump-puller, or lifting-machine, in combination with a suitable frame, a threaded lifting-rod, two lifters, and means for moving them up and down along the rod, their upward movements alternating with each other, nuts on the rod above the lifters respectively, affording stops by which the lifters may lift the rod in their respective upward movements, gear-pinions rigid with the nuts respectively, and a gear-train for driving such pinions to rotate the nuts, such gear-train being connected with the means for moving the lifters up and down, and means in such train for rotating the nuts alternately, each during the downward movement of the lifter with which it coöperates.

3. A stump-puller, or lifting-machine, comprising, in combination with a suitable frame, a threaded lifting-rod, two lifting-levers and means for vibrating them up and down along the rod, with their upward movements alternating, collars on the rod connected to said lifting-levers respectively, nuts on the rod above the collars respectively, affording stops by which the levers may lift the rod in their respective upward movements, and mechanism for vibrating the levers and rotating the nuts to cause the latter to follow the downward movements of the levers with which they respectively coöperate.

4. A stump-puller, or lifting machine, comprising, in combination with a suitable frame, a threaded lifting-rod, two lifting-levers fulcrumed on the frame, a link connecting them, two collars on the threaded rod pinioned respectively to the two levers at opposite sides of their respective fulcrums, means for actuating one of the levers, operating thereon at the opposite side from its fulcrum and of the collar pivoted from the link connection to the other lever, whereby the collars are each lifted while the other is lowered, nuts on the

threaded rod above the collars respectively, affording stops by which the levers, through the medium of the collars, may lift the rod, and means connected with the lever-operating mechanism to rotate the nuts, each during the descending movement of the collars with which they respectively coöperate.

5. A stump-puller, or lifting-machine, comprising, in combination with a suitable frame, a threaded lifting-rod, two levers and means for raising and lowering them alternately along the rod, nuts on the rod above the levers respectively, affording stops by which the levers may lift the rod in their respective upward movements, gears on the nuts for rotating them, and a gear-train extending to the nuts respectively, friction driving connections in the train leading to each nut, and means for driving such train during the movements of the levers in direction to screw the nuts downward on the rod, whereby, in each lifting movement, the train for driving the nut which affords the stop for such lifting, is rendered idle by the slipping at the friction connection, and the other train rotates its nut.

6. A stump-puller, or lifting-machine, in combination with a suitable frame, a threaded lifting-rod, two lifters and nuts on the rod coöperating therewith, a train for running the nuts down on the rod in the intervals of the lifting actions against them respectively, a train for operating the lifters, the frame of the first-mentioned train being sleeved on the rod whereby its position is determined by that of the rod, a gear in the lifting-train and a pinion meshing therewith having its bearing-frame pivoted about the axis of the gear, the driving-wheel on the pinion-frame and the driven wheel on the nut-operating train-frame, and means by which the former drives the latter, and a link connecting said frames whereby the change of position of the latter frame rocks the former about its fulcrum without changing the distance between said driving and driven wheels.

7. A stump-puller, or lifting-machine, comprising a threaded lifting-rod, a loose collar thereon, a nut above the collar by which the latter is checked longitudinally, lever mechanism connected to the collar, mechanism for holding the rod at position to which it may be lifted, independently of the collar, and means for rotating the nut during such holding, whereby the rotation of the nut on the thread is performed without friction due to stress of lifting or sustaining the weight.

8. In a stump-puller or lifting-machine, a threaded lifting-rod, two collars thereon, lever mechanism connected to the two collars for lifting them, nuts on the threaded rod above the collars respectively, to stop the collars longitudinally on the rod and afford abutments by which the collars may lift the rod, lever mechanism connected to the collars for alternately lifting them, and means for ro-

tating each nut, during the lifting action, on the collar stopped by the other nut.

9. A stump-puller or lifting-machine, comprising a threaded rod, two collars loose thereon, a lever and fixed support on which it is fulcrumed, a second lever suspended from the same support and linked to the first lever, the collars being pivoted to said two levers respectively, the first lever being fulcrumed on the fixed support at a point intermediate the pivotal connection of the collar thereto and the pivotal connection of the link which extends to the other lever, said other lever having the pivotal connection of the collar to it between its point of suspension and the point of the connection to it of the link; whereby the oscillation of said first lever in one movement lifts the collar pivoted to it, and in the other movement causes the other lever to lift its collar, nuts on the threaded shaft above said collars respectively by which the latter are stopped for lifting the rod, and means for rotating the nuts respectively on the shaft alternately at the times at which the lifting is being done by the opposite collars respectively.

10. A stump-puller or lifting-machine, comprising a threaded shaft, two collars loose thereon, two levers, one fulcrumed on the fixed support, the other suspended from such support and linked to the first lever, the collars being pivoted to the levers respectively, one in position to be lifted by the movement of the lever which causes its link connection to the other lever to descend, and the other by the movement of its lever which causes its link connection to the other lever to rise, nuts on the threaded rod above said collars respectively, by which the said collars are stopped for lifting the rod, a shaft having journal-bearings fixed with respect to one of the collars, and gears on said shaft meshing with the gear-teeth on the nuts respectively, said gears having friction driving connection with said shaft, one above and the other below the gear, and means for rotating said shaft whereby the oscillation of one of the levers causing the friction connection to operate alternately upon the two gears as the lever is moved alternately in opposite directions, drives the two nuts alternately, and in the intervals lifts the two collars alternately.

11. A stump-puller or lifting-machine, comprising a threaded rod, a bracket comprising a collar loose on the rod, a pinion screwed onto the rod above the collar, a second pinion screwed onto the rod and a collar below it loose on the rod, adapted to lift the latter by being stopped against the pinion, a shaft, gears loose thereon, engaging the pinions respectively, frictional disks on the shaft for driving the loose gears respectively, a lever fulcrumed on the fixed support, and a second lever suspended from such support and linked to the first lever, the two collars being pivoted to said two levers respectively, one at

- the opposite side of the lever's fulcrum from its link connection with the other lever, and the other at the same side of the lever's fulcrum and between said fulcrum and the link connection, whereby the movement of the first lever in one direction lifts one of the collars, and in the other direction causes the other lever to lift the other collar, and means for operating said first lever.
- 10 12. A stump-puller or lifting-machine, comprising a threaded rod, a bracket comprising a collar loose on the rod, a pinion screwed onto the rod above the collar, a second pinion screwed onto the rod, and a collar below it loose on the rod, adapted to lift the latter by being stopped against the pinion, a shaft, gears loose thereon, engaging the pinions respectively, frictional disks on the shaft for driving the loose gears respectively, a lever fulcrumed on the fixed support, and a second lever suspended from such support and linked to the first lever, the two collars being pivoted to said two levers respectively, one at the opposite side of the lever's fulcrum from its link connection with the other lever, and the other at the same side of the lever's fulcrum and between said fulcrum and the link connection, whereby the movement of the first lever in one direction lifts one of the collars, and in the other direction causes the other lever to lift the other collar, and means for operating said first lever; a gear-train comprising a wheel having a crank-wrist or equivalent means for oscillating the lever connected thereto, said train extending to and comprising also means for rotating the shaft,
- 15 whereby the lifting action of the lever is performed simultaneously by the rotation of the shaft, and the frictional resistance caused by such lifting, acting alternately upon the two pinions respectively, causes the said pinions to be rotated alternately, each during the lifting action performed by means of the other.
- 20 13. A stump-puller or lifting-machine, comprising in combination with a suitable frame, a threaded lifting-rod, two levers and means for raising and lowering them alternately along the rod; nuts on the rods above the levers respectively, affording stops by which the levers may lift the rod in their respective movements; nuts and gears for rotating them, and gear-trains extending to the gears respectively; friction driving connections in the train leading to each nut and means for driving such train during the movements of the levers adapted to be rotated in direction to screw the nuts upward on the rod; mechanism for locking each nut-operating train and releasing the other train, arranged to be operated for such locking and release by the moving train after so much movement only as advances the nut operated by such train on the rod a distance equal to the lift of the lever in one oscillation.
- 25 In testimony whereof I have hereunto set my hand, in the presence of two witnesses, at Chicago, Illinois, this 4th day of April, A. D. 1902.
